CLAIM

The ornamental design for a battery cover, as shown and described.

DESCRIPTION

FIG. 1 is a front, bottom, and left side perspective view of a first embodiment of a battery cover;
FIG. 2 is a top plan view of the first embodiment;
FIG. 3 is a right side elevation view of the first embodiment;
FIG. 4 is a front elevation view of the first embodiment;
FIG. 5 is a left side elevation view of the first embodiment;
FIG. 6 is a rear elevation view of the first embodiment;
FIG. 7 is a bottom plan view of the first embodiment;
FIG. 8 is a front, bottom, and left side perspective view of a second embodiment of a battery cover;
FIG. 9 is a top plan view of the second embodiment;
FIG. 10 is a right side elevation view of the second embodiment;
FIG. 11 is a front elevation view of the second embodiment;
FIG. 12 is a left side elevation view of the second embodiment;
FIG. 13 is a rear elevation view of the second embodiment; and,
FIG. 14 is a bottom plan view of the second embodiment. The broken line matter in all figures is for illustrative purposes only and forms no part of the first embodiment.
